[57] CLAIM

The ornamental design for a heat dissipation fan, as shown and described.

DESCRIPTION

FIG. 1 is a perspective view of the heat dissipation fan in accordance with the first embodiment of the claimed design;

FIG. 2 is a top plan view thereof;

FIG. 3 is a right side elevational view thereof;

FIG. 4 is a front elevational view thereof;

FIG. 5 is a rear elevational view thereof;

FIG. 6 is a left side elevational view thereof;

FIG. 7 is a bottom plan view thereof;

FIG. 8 is a perspective view of the heat dissipation fan in accordance with the second embodiment of the claimed design;

FIG. 9 is a top plan view of FIG. 8;

FIG. 10 is a right side elevational view of FIG. 8;

FIG. 11 is a front elevational view of FIG. 8;

FIG. 12 is a rear elevational view of FIG. 8;

FIG. 13 is a left side elevational view of FIG. 8; and,

FIG. 14 is a bottom plan view of FIG. 8.
